D. A. LEIGH

VACUUM AND PRESSURE GOVERNOR, REGULATOR, OR CONTROL

Filed Oct. 9, 1922

Don A. Leigh
Inventor

By his Attorney
Alfred H. Faber

UNITED STATES PATENT OFFICE.

DON A. LEIGH, OF FELLOWS, CALIFORNIA.

VACUUM AND PRESSURE GOVERNOR, REGULATOR, OR CONTROL.

Application filed October 9, 1922. Serial No. 593,471.

To all whom it may concern.

Be it known that I, DON A. LEIGH, a citizen of the United States, residing at Fellows, in the county of Kern and State of California, have invented a new and useful Vacuum and Pressure Governor, Regulator, or Control for Use upon Gas and Air Lines, of which the following is a specification.

In the present state of the oil industry, 10 natural gas is becoming increasingly valuable, because of discovery of means of removing its gasoline content by absorption and compression processes, as well as its use for fuel by the producing companies, 15 and its salability to gas companies for the purpose of light and fuel. The saving of such gas forms an important branch of oil production methods, and mechanical means are resorted to in order to recover and save 20 the gas as the same issues from the wells, and to accelerate the flow thereof through pipe-lines to the plants where such gas is to be used.

Such result is effected by means of pumps 25 of various types producing vacuum on one side, withdrawing gas from the casing head of the well, or through a gas trap, separating the gas from the oil as the oil is pumped from the well, and causing it to flow towards the vacuum pump. At the pump, the 30 gas is taken through the valves of the pump, and as it passes beyond, pressure is applied, and the gas is forced forward to its ultimate destination.

One pump may serve one or many wells, and it is apparent that the well nearest the pump will at all times be subject to the greatest vacuum, to the detriment of wells located at a greater distance. It is desirable 40 under ordinary conditions, to take the gas from the well at atmospheric pressure, and prevent the vacuum from acting on either the casing head or gas trap. In many cases, where such vacuum is applied direct, without 45 the intervention of any regulating apparatus, the power exerted by the suction of the vacuum pump is sufficient to pull the oil or fluid content of the gas trap, over and out of the same and into the gas line, causing 50 difficulty in freeing the line, and a loss of gas and oil.

To overcome this loss and equalize the vacuum exerted at each of a series of wells served by the same pipe-line, leading to the 55 same vacuum pumping plant, I apply upon the gas line at a convenient distance from

the casing head or gas trap, the device illustrated in the accompanying drawing, in which

Fig. 1 is a plan of the device, showing its 60 location and attachment to the gas line from the casing head or gas trap at the well; and Fig. 2, is an elevation of the same device, with parts thereof exposed, showing internal operation.

Similar numerals in the two views are identical, and refer to the same part of the device.

Flow of casing head gas from an oil well is intermittent in time and irregular in quantity. During an intermission of flow, the gaseous contents of the pipe (1), are exhausted or attenuated by means of the vacuum pump, and this vacuum is extended through the smaller pipe (6), and exhausts 75 the contents of the chamber of piston, (2), thereby causing the piston plunger (8), to be drawn backward, moving with it the piston rod (5), engaging and rotating the geared wheel (4), imparting motion to its axle, and 80 closing the diaphragm of the butterfly valve (3). This interposes an obstacle to the further action of such vacuum pump beyond such butterfly valve, and releases it for action upon other wells connected with such pipe line, and prevents the lifting or withdrawal 85 of the fluid contents of the gas trap, by means of such suction, into the pipe-line; or the exertion of further vacuum upon the casing head or gas trap.

To prevent intake of air through the piston cylinder (2), the gland of the plunger (8), rests accurately against the shoulder (9), securely sealing same from all access 90 of air, and avoiding any vitiation thereby 95

When a flow of gas later occurs from such well, it accumulates in the casing head or gas trap, flows into the pipe-line, and by means of pipe (6), into the chamber of the piston (2), where, by reason of its further progress being impeded by the butterfly valve (3), it exerts a pressure on the piston plunger (8), forces it forward together with the piston rod (5), engaging the geared wheel (4), rotating it on its axis, and thereby opening the diaphragm of the butterfly valve (3), whereupon it is taken up by suction from the vacuum pump, and withdrawn through the pipe-line to its destination. An 100 oil cup (7), with needle valve, is tapped into the crown of the piston, and lubricates the 105 110

plunger (8), maintaining the freedom of its movements as the same is incessantly actuated by the fluctuating pressure or vacuum in the chamber of the piston.

5 I claim—

1. In a pipe-line, or other tubular device for the conveyance of gas, or other lighter than air substances, where the contents thereof are at times under greater than atmospheric pressure, and at other times under the same or less than such pressure, a valve of suitable type affixed within such pipe-line or device, by a transverse shaft, one end of which extends through such pipe, 10 to which there is externally affixed a cogged wheel; a toothed rod engaging such cogged wheel, and which rod at its opposite end is attached to a piston, operating within a cylinder, one end whereof is open to the atmosphere, and the opposite end thereof is connected beyond the point of movement of said piston, by a pipe connected with the said pipe line, freely admitting the contents of such pipe-line when 15 in pressure, or having such piston chamber exhausted of such contents when said pipe-line is at less than atmospheric pressure, whereby said piston is driven forward when such pressure is exerted, or drawn in the opposite direction when in vacuo, thereby 20 controlling the action of said valve; within which cylinder and forming an integral part thereof there is affixed a shoulder or flanged rim against which the gland of the piston plunger accurately rests, when such piston plunger is drawn inward by the suction of the vacuum in said piston chamber and pipe line; and together with a tapped entrance or 25 duct on said cylinder to receive the stem of an oil 30

cup for the purpose of lubricating the same 40 when the plunger therein is in action.

2. In a pipe-line, or other tubular device for the conveyance of air, where the contents thereof are at times under greater than atmospheric pressure, and at other 45 times under the same or less than such pressure, a valve of suitable type affixed within such pipe-line or device, by a transverse shaft, one end of which extends through such pipe, to which there is externally affixed a gear wheel; a gear rack engaging such gear wheel, and which rack at its opposite end is attached to a piston, operating within a cylinder, one end whereof is open to the atmosphere, and the opposite end thereof is connected beyond the point 50 of movement of said piston, by a pipe connected with the said pipe line, freely admitting the contents of such pipe-line when in pressure, or having such piston chamber exhausted of such contents when said pipe-line is at less than atmospheric pressure, whereby said piston is driven forward when such pressure is exerted, or drawn in the opposite direction when in vacuo, thereby 55 controlling the action of said valve; within which cylinder and forming an integral part thereof there is affixed a shoulder or flanged rim against which the gland of the piston plunger accurately rests, when such piston plunger is drawn inward by the suction of the vacuum in said piston chamber and pipe line; and together with a tapped entrance or 60 duct on said cylinder to receive the stem of an oil cup for the purpose of lubricating the same when the plunger therein is in action. 65

DON A. LEIGH.
